[57] CLAIM

The ornamental design for a bench, as shown and described.

DESCRIPTION

FIG. 1 is a perspective view of a bench which embodies my design;

FIG. 2 is a top plan view thereof;

FIG. 3 is a front elevational view thereof;

FIG. 4 is a right-side elevational view thereof;

FIG. 5 is a rear elevational view thereof;

FIG. 6 is a left-side elevational view; and,

FIG. 7 is a bottom plan view thereof.

The broken line showings in the drawing figures are for illustrative purposes only and form no part of the claimed design.
